UNITED STATES PATENT OFFICE.

CHARLES B. CORBIN, OF GRAND RAPIDS, MICHIGAN, ASSIGNOR OF ONE-HALF TO MICHIGAN TOOL AND STAMPING WORKS, OF GRAND RAPIDS, MICHIGAN.

EXTENSIBLE BRACKET.

No. 922,566.

Specification of Letters Patent. Patented May 25, 1909.

Application filed April 3, 1909. Serial No. 487,817.

To all whom it may concern:

Be it known that I, CHARLES B. CORBIN, a citizen of the United States, residing at Grand Rapids, in the county of Kent and 5 State of Michigan, have invented certain new and useful Improvements in Extensible Brackets, of which the following is a specification.

My invention relates to improvements in 10 extensible brackets for use, particularly, with wardrobe hooks and hangers, though serviceable in any place where an extensible bracket is needed, and its objects are: First, to provide an extensible bracket that will 15 render the greatest possible amount of rigidity with the least possible number of parts and the simplest form of construction. Second, to provide an extensible bracket that may be readily put up, taken down, or ad- 20 justed, and, third, to provide an extensible bracket that is capable of supporting extremely heavy loads without too great strain upon its working parts.

I attain these objects by the mechanism 25 illustrated in the accompanying drawing, in which Figure 1 is an elevation of this bracket as mounted for the support of extremely heavy loads, as in suit cases in large furnishing stores. Fig. 2 is a top plan of the same. 30 Fig. 3 is an elevation of a bracket with the auxiliary support removed and hooks pro- 35 vided for supporting garments, in lieu of the supporting bar shown in Fig. 1, and, Fig. 4 is an elevation of the supporting post and its bracket.

Similar letters refer to similar parts throughout the several views.

In the construction of this bracket I utilize the ordinary form of cross extensions, con- 40 sisting of links D pivoted together at the ends, as at d, and at the center, as at d', with the first link pivoted at the upper end to the supporting post C, and the lower end of the first link slidably secured at the lower end of 45 the supporting post C, as indicated by the rivet C' working in the slot b. The last pair of links, D', are made a trifle longer than one half the length of the links D, so that considerable more space exists between the points e 50 and f, than between any two of the points d', for the purpose of giving the greatest possible amount of leverage for the supporting arm

F, which is pivotally secured to the links D, at f.

The arm E is pivotally secured to the ends 55 of the links D', as at e, and has two loops, G, securely attached to it and extending upward to position so that the arm F may pass through them, forming a fulcrum at the extreme back end of the arm E, and a proper 60 leverage over this fulcrum and between the pivot point f and the forward loop G to permit of great weight being suspended from the extreme outer end of the arm E without 65 danger of causing these arms to sag under 70 the weight. It will be readily understood that with this construction, the entire series of links, from the point f back to the upper pivot in the supporting post C, will act as a series of well arranged braces, which will 75 render the bracket, practically, as firm under a steady strain, as if the arms E and F were firmly secured and braced in the supporting post C. Another very desirable object at- 80 tained by this construction, is that as the 75 bracket is being extended the length of leverage between the points e and f is con- 85 stantly increasing, so that the supporting capacity of the bracket is practically the same when fully extended, to the positions 80 indicated by the dotted lines in Figs. 1 and 3, as when thrown back to the position of the solid lines in these figures.

For ordinary use the bracket, in its sim- 85 plest form, hereinbefore described, is suf- ficiently strong and rigid to support any weight that may be placed upon it, and with this form I provide a series of hooks, J, upon which to hang the different articles it is desired to place on the bracket, and a hand 90 piece, J', with which to manipulate the bracket.

In the construction of this bracket, the extensible portion is made with two links, D D passing, successively from the pivot 95 point at the head or top of the supporting post C, diagonally downward and inclining away from the post, and a single link passing diagonally from the pivot point C' upward between two of the oppositely inclined links 100 and there pivoted properly to give the best results, and so continued until the desired extensible portion is formed, and each of the arms E and F are made of two side plates

securely riveted together, as indicated at e' , so that they must stand absolutely rigid and, with the guidance of the loops G , must always be in exact alinement and bear 5 closely together, so that the sustaining or supporting properties will be absolutely sustained, no matter whether the bracket is extended or withdrawn.

When this bracket is designed to support 10 very great weights, as when used to store a great many suits of men's clothing, I find it much better to provide an auxiliary support, and for this purpose I provide for placing supporting rails, as H , in the upper portion 15 of the case, or other receptacle for the brackets, and securely attach one end of these rails to the support B , and the other end to any desired form of support, as the depending arms K K , so arranged that anti-friction rollers or small wheels, h , may be so secured at the point of conjunction of the 20 upper ends of the links D and D' , as to travel freely upon, and be supported by the rails H , as indicated in Figs. 1 and 2. With 25 this form of bracket I find it more convenient to replace the hooks J with a rail I , which I secure at one end, to the outer rivet e' in the arm E , whence it extends directly downward for a distance, and is then bent backward 30 to form the supporting rail I , parallel with the arm E , with the back end extending back far enough to be passed through, and supported by the link I' , which is, preferably, suspended from the rivet f , and may be provided with an antifriction roller i over which 35 the rail will move freely as the bracket is being extended or withdrawn. When this construction is used the loop J' may be dispensed with, as the upright portion, i' , of 40 the rail I may be utilized for manipulating the bracket.

A represents the wall, or back of the case to which the supporting bracket B is securely attached. This bracket is bent at right 45 angles at each end, and prepared to form a pivotal connection with the post C , so that this post may be made to turn readily therein. In constructing the post C the upper pivot, c , is made long, while the corresponding lower pivot is made short, so that the post C may be readily removed from the bracket B by simply raising it upward and drawing the lower end outward, as soon as the lower pivot has raised out of its bearing 55 at the lower end of the bracket B . This supporting post is made open, as indicated in Fig. 4, so that the links D may be placed and pivoted between them, as indicated in Figs. 1 and 3. It will be readily seen that by 60 the construction hereinbefore described, the links are so pivoted together, and to the supporting post C , as to obtain the greatest possible amount of strength and utility from the rivets d and d' , with the least possible danger

of shearing or cutting them off, working them loose, or bending and cramping them in their bearings. 65

At i' , in Fig. 3, I have shown a loop that may be suspended from the links D D' for receiving and storing neck ties, ribbons, or other small articles that the owner might desire to place in said loop. 70

What I now claim as new, and desire to secure by Letters Patent of the United States, is: 75

1. In combination with links pivoted together at the ends and centers to form an extensible construction, a pair of short links pivoted at one end to the free ends of the two end links of the extension, an arm pivoted to the free ends of these short links and having loops extending upward, a second arm made to slide freely in these loops, and pivotally secured to the crossing point of the links in the extensible construction. 80

2. In combination with a supporting post, a link pivotally secured to the upper end of said post, a link slidably secured at the lower end of said post, said links crossed and pivoted together at the point of crossing, a series of corresponding links pivoted together at the ends and at the crossing points to form an extensible construction, short links, but over half length, pivoted to the ends of the last of the series of links, an arm pivoted to the free ends of these short links and having a loop at the end and a loop some distance therefrom and both loops extending upward, an arm passed through said loops and pivoted at one end to the crossing point of links in the extensible series, and appliances on one of the arms for receiving and supporting articles. 90

3. In combination with a supporting post, an extensible construction of crossed links properly secured to said post, short terminal links, an arm pivotally secured to said short links and having loops extending upward, an arm made to slide freely in said loops and pivoted, at one end to the crossing point of the adjacent links of the extensible construction, a link extending downward from the pivoted end of this arm, and an appliance for receiving and supporting articles, secured at one end to the end of the lower arm and the other end supported by said links. 100

4. In combination with a supporting bracket, a supporting post revolvably secured in said bracket in such a manner that it may be readily removed, a cross linked extensible construction properly supported in said post, short outer links in said construction, an arm pivotally secured to the ends of the short links and having two loops extending upward from it near the back end, an arm made to slide freely in said loops and with one end pivotally secured to the crossing point of adjacent links. 110

5. In combination with a supporting post, a series of crossed links connected therewith to form an extensible construction, short links at the end of said construction, an arm 5 pivoted to the ends of said short links and having loops extending upward from said end, an arm made to slide freely in said loops and having one end pivotally secured to the adjacent cross links, and supporting rails above the arms in position to support the 10 upper end of the links and allow them to slide freely thereon.

Signed at Grand Rapids, Michigan, March 20, 1909.

CHARLES B. CORBIN.
